UNITED STATES PATENT OFFICE.

HENRY L. PITMAN, OF WESTFIELD, NEW JERSEY, ASSIGNOR TO UNDERWOOD COMPUTING MACHINE COMPANY, OF NEW YORK, N. Y., A CORPORATION OF NEW YORK.

COMPUTING MACHINE.

Application filed October 23, 1920. Serial No. 418,913.

To all whom it may concern:

Be it known that I, HENRY L. PITMAN, a citizen of the United States, residing in Westfield, in the county of Union and State 5 of New Jersey, have invented certain new and useful Improvements in Computing Machines, of which the following is a specification.

This invention relates to error-preventing 10 means for combined typewriting and computing mechanism.

It has been possible heretofore to operate the error key before the completion of the 15 operation of the general operator, and also to start the general operator into action before the completion of the operation of the error key. This condition is disadvantageous at all times, in that operation of either mechanism will obstruct the operation 20 of the other, and is particularly so in case of a machine adapted to be set for subtraction in the same general manner as the machine shown in the patent to Minton, No. 1,280,065, of September 24, 1918. In 25 said patent, the subtraction-bar is automatically released upon entrance into a subtraction zone thereby effecting a preliminary setting of the "9" pins, and the latch to hold the subtraction-bar in ineffective position

30 will be maintained in ineffective position after its release until the carriage is moved out of the subtraction zone, so that if the general operator is actuated in a subtraction zone and the subtraction-bar moved forward- 35 ly, the latter will be permitted to return to subtraction-setting position, thereby resetting the "9" pins. The mechanism of this patent may be equipped with error key mechanism of the same general form as that dis- 40 closed in the patent to Walsleben, No. 1,255, 828, of February 5, 1918.

In case an error is made in indexing in a subtraction zone, it would be necessary to operate the error key and restore the index 45 pins to their normal positions and then to set the motor into operation to cause the general operator to move through a cycle in which, as fully described in said Minton patent, the subtraction-bar is drawn forward, latched in forward position and then released as the general operator approaches its normal position, so as to reset the "9"

pins preparatory to again indexing for subtraction. If, however, the error key is held depressed during the complete reciprocation of the general operator, the pin-engaging bar of the latter will pass over the pin-resetting platform, but at the time of the movement of the subtraction bar to reset the "9" pins, the pin-resetting platform will be in elevated position and prevent the proper setting of the "9" pins. Consequently, the indexing of the pins for complementary subtraction will not be properly effected and computation resulting from operation 65 of the general operator will result in an incorrect reading.

The main object of this invention is to provide simple and efficient means whereby such difficulties may be avoided.

In carrying out the invention, provision may be made of means whereby depression of the error key will prevent actuation of the general operator by either the usual motor-starting key adjacent the keyboard 75 or the slide through which the automatic starting of the motor is usually effected. The means just referred to may also be adapted to lock the error key in case either the motor-starting key or the slide is ac- 80 tuated.

Provision may be made of means controlled by the general operator, whereby the error key will be locked when the general operator is out of normal position.

Provision may be made of connections between the error key and suitable locking means for the numeral keys to cause the latter to be locked when the error key is depressed.

Further provision may be made of means to cause actuation of the general operator and to concomitantly lock the numeral keys.

Other features and advantages will hereinafter appear.

In the accompanying drawings,

Figure 1 is a sectional side view, showing my invention applied to so much of an Underwood-Hanson computing machine as is necessary for purposes of illustration.

Figure 2 is a sectional view, showing part of the mechanism whereby restoration to normal position of depressed pins is effected when the error key is depressed.

Figure 3 is a view showing certain of the parts in the positions assumed when the error key is depressed.

Figure 4 is a view of certain of the parts shown in Figure 1, but showing these parts in error-key-locking position due to movement of the general operator.

Upon actuation of a numeral key 10, a pendant or link 11 pivoted thereto will act 10 on a lever 12 to rock a shaft 13 on which said lever is fixed. Rocking of the shaft 13 effects, by means of an arm 14 secured thereon, a pin-setting movement of a linkage having a lower bar 15 adapted to set a pin 15 16 on a selected pin-bar or denominational member 17. The pins on said bars are normally to the rear of the paths of the bars 15, and are brought into position to be actuated by said bars by suitable denominational-selecting means which will cause the denominational members 17 to be advanced seriatim to positions to permit pin-setting. This denominational-selecting means may be substantially the same as that disclosed in 25 the patent to Hart, No. 1,287,301, of December 10, 1918, and comprises rods or thrust 30 links 18, which, when actuated, will swing corresponding levers 19 about their pivots, and, by means of transposition linkages 20 and bell-crank 21 engaging pins 22 on the respective denominational members 17, advance the latter to pin-setting positions.

After a number has been indexed on the pins 16 of the proper pin-bars or denominational members 17, a motor-starting key 35 may be depressed against the action of a spring 24, thereby swinging a lever 25 about its pivot 26 to depress the right-hand end 40 of a lever 27, thereby lifting a motor-trip pin 28 and releasing the motor, which, by means of a member 29 projecting into a yoke 30 on the general operator 31, will cause the latter to be reciprocated. Upon forward movement of the general operator, 45 bar 32, constituting a part thereof, will engage the depressed pins 16 and actuate the denominational members 17 to actuate, in accordance with the pins set, dial wheels 33, to which said pin-bars 17 are suitably geared, the result of the computation being read through a sight-opening 34. Upon return of the general operator, the pin-bars 17 will be restored to 50 their normal positions and the depressed pins will be reset in the usual manner. The connections for starting the motor may be in general the same as those disclosed in the co-pending application of Carl E. Norin, No. 309,836, filed July 10, 1919, now Patent 60 No. 1,370,475, dated March 1, 1921 and the motor controlled by the pin 28, as well as the connection between the motor and the general operator, may be substantially the same as in the patent to Alfred J. Wood, 65 No. 1,299,646, dated April 8, 1919.

It should be understood that more than one register comprising dial wheels 33 may be provided; a set of pin-bars and denomination-selecting mechanism being associated with each register but the pin-setting linkage being common to all of the sets of pin-bars.

Provision may be made of subtraction-setting mechanism having many features in common with that disclosed in said Minton patent. As herein disclosed, the depression of a subtraction key 35 will move a link 36 against the resistance of a spring 37, and, by means of an arm 38 fixed on shaft 39, rock the latter to withdraw a hook 40 from engagement with a shoulder on a subtraction-bar 41, permitting the latter to be drawn to the rear by a spring 42. Such movement of the subtraction-bar 41 will effect, through a bell-crank 43 and an arm 44 connected to a bar 45 pivoted near its upper edge, rocking of bar 45 and thereby shift the shafts 13 to change the connection between the arms 14 and the pin-setting linkages. As a result of such change, the shafts 13, when rocked, will actuate the pin-setting linkages which are complementary, to the base nine, of the linkages actuated thereby when the shafts 13 are in their normal positions. The rearward movement of subtraction-bar 41 will also effect, through connections not shown, depression of all of the "9" pins by means of a bar 46. As is well known to those skilled in the art, the parts are now positioned to enable indexing a number for subtraction by the complementary method.

Provision may also be made of a pivoted lever 47 corresponding to one shown in the Minton patent, in which it forms part of the mechanism by which automatic tripping of the motor is effected. The forward end of this lever overlies a pin 48 on a vertically movable slide 49 engaging lever 27 near its right-hand end, so that, upon elevation of the rearward arm of lever 47, the controlling pin 28 will be lifted and the motor thrown into action to reciprocate the general operator. As disclosed in said Minton patent, the slide corresponding to slide 49 serves as a key, but, in the machines now in use, manual operation of the motor-trip mechanism is effected by the key 23, and the slide 49 is used only in connection with the automatic tripping of the motor. Elevation of the rearward arm of lever 47 will also effect, through an arm 50 mounted on a shaft 51, actuation of the shaft and an arm 52 thereon to shift a slideable latch member 53 against the action of a spring (not shown), thereby releasing an arm 54 mounted on a shaft 55, so that the latter may be rocked by means of a spring 56, a plate 57 connected therewith, and an arm 58 having

a pin-and-slot connection with arm 54. Such rocking of shaft 55 will swing an arm 59 thereon to the rear, and, by means of a link 60 connecting the latter to an arm 61, rock a shaft 62 to carry an intruding arm 63 between the crowding members 64, thereby locking the numeral keys by blocking links 65 connected with the pendants 11. Upon actuation of the general operator, a member 57^a will be swung about its pivot and will engage plate 57 and restore the same to position to be engaged by latch member 53 thus unlocking the numeral keys.

In case an error is made in indexing a number by means of the pins 16, it may be desirable to restore all of the set pins to their normal positions to enable the number to be indexed correctly. This may be done by depressing an error key 66 against the action of spring 67. The key 66, when depressed, rocks an arm 68 about its pivot 69, and, by means of a link 70, rocks a bell-crank 71 against the action of its returning spring 72 to advance a link 73 and lift pin-restoring platform 74 by means similar to that disclosed in said patent to Walsleben.

The pin-restoring platform may be supported at each end by bell-cranks 75, the bell-cranks at the front being connected with those at the rear by means of a link or links 76, and downward movement of the pin-restoring platform being limited by means of an arm 77 movable with the forward bell-cranks 75 and engaging, when the pin-restoring platform is in its lowest position, a member 78 beneath the pin-restoring platform and connected thereto. The link 73 is slidably supported at its rear end by a pin 79 extending through a slot in a bracket 80. When the link 73 is moved to the rear, it will tension a spring 81 connected to pin 79 and to the downwardly-extending arm of a bell-crank 82 pivoted at 83 on the bracket 80, and, as the link 73 approaches the rearward limit of its movement, a pin 84 thereon will engage the downwardly-extending arm of a latching bell-crank 85, swinging the upper arm thereof out of the path of a stud 86 on the bell-crank 82 and releasing the latter to the action of the spring 81, which will swing the bell-crank 82 in a counter-clockwise direction and cause its rearwardly-extending arm to engage a pin 87 on one of the rear bell-cranks 75, thereby effecting upward movement of the pin-restoring platform 74. A spring 88 connected with a pin 89 and the bell-crank 85 normally holds the latter in its latching position against pin 89. As will be seen from an inspection of Figure 2, the pin-restoring platform is provided with downwardly-inclined ends, so that, if the general operator is actuated when the pin-restoring platform is held in its upper position by spring 81, the bar 32

of the general operator will cam the pin-restoring platform downwardly so as to pass thereover.

Depression of the error-key 66 also causes a pin 90 on a bracket projecting from the stem of the error key to actuate an arm 91 on a shaft 92 to rock the latter against the action of a spring 92^a, and by suitable means to prevent actuation of the motor-trip mechanism. In effecting this result, the movement of the shaft 92 is transmitted, by means of an arm 93 fixed thereon, to a link 94 slidably supported at its rear end by the pivot 26 passing through a slot therein. The link 94 in its movement carries a cam-member 95 secured thereto under a pin 96 on the lever 25 and a cam-member 97 under a stud 98 on slide 49, thereby locking the starting key 23 and the slide 49 against actuation.

It will also be seen that depression of either key 23 or slide 49 may lock the error key by moving pin 96 or stud 98 into the path of cam-member 95 or cam-member 97, respectively.

Provision may also be made of error-key locking means controlled by the general operator, such means comprising a bell-crank 99 on pivot 26, the upwardly-extending arm of the bell-crank being engaged by the bar 32 of the general operator, so that when the bar 32 is in its normal position, the forwardly-extending arm 100 of the bell-crank will be held in raised or ineffective position. Upon forward movement of bar 32, the bell-crank 99 will be released, and in case the link 94 is in its normal position, an off-set portion 101 on arm 100 will be brought down in front of an upward projection 102 on link 94 so as to lock against movement of the link 94, and consequently the error key. A suitable guiding member 103 for arm 100 may be provided. Upon release of the bell-crank 99, the weight of the forwardly-extending arm 100 will cause the projection 101 to be moved into operative position, but, if found desirable, such movement of the bell-crank may be insured by any suitable means, such as a spring.

It may be desirable also to lock the numeral keys when the error key 66 is in depressed position. To this end, provision is made of an arm 104 fixed on shaft 92, and connected by means of a link 105 to a bell-crank 106 loosely mounted on shaft 55, the free end of the bell-crank 106 being in engagement with a cam-surface 107 on a slide 108, so that on actuation of the error key and consequent rocking of the bell-crank 106, the slide 108, which is connected with the latch-member 53, will move the latter to the rear to release the arm 54, and thereby effect locking of the numeral keys as hereinbefore described.

The usual shaft 109, to which an operating handle (not shown) may be attached, is con-

nected by means of sectors 110 and pinions 111 to racks 112 on the general operator 31. It should be understood that shaft 109 is utilized in controlling the operations of 5 different parts of the computing machine, one use being disclosed in said patent to Minton.

Variations may be resorted to within the 10 scope of the invention, and portions of the improvements may be used without others.

Having thus described my invention, I claim:

1. In combination, computing mechanism comprising devices in which numbers may 15 be indexed and a general operator whereby numbers so indexed may be computed, actuating means for said general operator, an error key, error-key-actuated means whereby the index-devices may be restored to normal 20 condition, and means whereby actuation of said error key will prevent actuation of said general operator.

2. In combination, computing mechanism comprising devices in which numbers may 25 be indexed and a general operator whereby numbers so indexed may be computed, a motor, motor-actuated means for actuating said general operator, a motor-trip device, a member by which said motor-trip device 30 may be operated, an error key, error-key-actuated means whereby the index-devices may be restored to normal condition, and means whereby actuation of said error key 35 will prevent operation of said motor-trip device by said member.

3. In combination, computing mechanism comprising devices in which numbers may 40 be indexed and a general operator whereby numbers indexed may be computed, a motor, motor-actuated means for actuating said 45 general operator, a motor-trip device, a member by which said motor-trip device may be operated, an error key, and error-key-actuated means whereby the index-devices may be restored to normal condition, including means for locking said member against movement.

4. In combination, computing mechanism comprising devices in which numbers may 50 be indexed and a general operator whereby numbers indexed may be computed, a motor, motor-actuated means for actuating said 55 general operator, a motor-trip device, a member by which said motor-trip device may be operated, an error key, and error-key-actuated means whereby the index-devices may be restored to normal condition, including a member which upon operation of said 60 error key will be moved into engagement with the motor-trip member and lock the same against movement.

5. In combination, computing mechanism comprising devices in which numbers may 65 be indexed and a general operator whereby numbers so indexed may be computed, a

motor, a motor-trip device, a key to operate said motor-trip device directly, a second key, a lever actuatable by said second key and positioned to engage the motor-trip device, an error key, error-key-actuated means whereby the index-devices may be restored to normal condition, and error-key-actuated means for locking said first key and the lever controlled by said second key against movement.

6. In combination, computing mechanism comprising devices in which numbers may be indexed and a general operator whereby numbers so indexed may be computed, a 70 motor, a motor-trip device, a manually-operable device for operating said motor-trip device, a separate device for operating said motor-trip device, an error key, and error-key-controlled means for blocking both of the last-mentioned devices to prevent operation 75 thereby of the motor-trip device.

7. In combination, computing mechanism comprising numeral keys, devices in which numbers may be indexed in accordance with the numeral keys depressed, and a general operator whereby numbers so indexed may be computed, actuating means for said general operator, an error key, error-key-actuated means whereby the index devices may be restored to normal condition, means whereby actuation of said error key will prevent actuation of the general operator, and means whereby said numeral keys will be locked upon actuation of said error key.

8. In combination, computing mechanism comprising devices in which numbers may be indexed and a general operator whereby numbers so indexed may be computed, actuating means for said general operator, an error key, error-key-actuated means whereby the index devices may be restored to normal condition, means whereby actuation of said error key will prevent actuation of said general operator, and locking means for said error key controlled by said general operator.

9. In combination, computing mechanism comprising devices in which numbers may be indexed and a general operator whereby numbers so indexed may be computed, actuating means for said general operator, an error key, error-key-actuated means whereby the index devices may be restored to normal condition, means whereby actuation of said error key will prevent actuation of said 110 general operator, and an error-key lock normally held in ineffective condition by said general operator but permitted to become effective upon movement of the general operator from its normal position.

10. In combination, computing mechanism comprising numeral keys, devices in which numbers may be indexed in accordance with the numeral keys depressed, and a general operator whereby numbers so indexed may 120

be computed, a motor, motor-actuated means for actuating said general operator, a motor-trip device, a member by which said motor-trip device may be operated, an error key, error-key-actuated means whereby the index devices may be restored to normal condition, means whereby actuation of the error key will prevent operation of the motor-trip device by said member, and locking means for said numeral keys rendered effective upon actuation of said error key.

actuated means whereby the index devices may be restored to normal condition including means for locking said member against movement, and locking means for said error key controlled by the general operator.

11. In combination, computing mechanism comprising devices in which numbers may be indexed and a general operator whereby numbers so indexed may be computed, a motor, motor-actuated means for actuating said general operator, a motor-trip device, a member by which said motor-trip device may be operated, an error key, error-key-actuated means whereby the index devices may be restored to normal condition, means whereby actuation of the error key will prevent operation of the motor-trip device by said member, and locking means for said error key controlled by the general operator.
15. numbers so indexed may be computed, a motor, motor-actuated means for actuating said general operator, a motor-trip device, a member by which said motor-trip device may be operated, an error key, error-key-actuated means whereby the index devices may be restored to normal condition, means whereby actuation of the error key will prevent operation of the motor-trip device by said member, and locking means for said error key controlled by the general operator.
20. numbers so indexed may be computed, a motor, motor-actuated means for actuating said general operator, a motor-trip device, a member by which said motor-trip device may be operated, an error key, error-key-actuated means whereby the index devices may be restored to normal condition, means whereby actuation of the error key will prevent operation of the motor-trip device by said member, and locking means for said error key controlled by the general operator.
25. numbers so indexed may be computed, a motor, motor-actuated means for actuating said general operator, a motor-trip device, a member by which said motor-trip device may be operated, an error key, error-key-actuated means whereby the index devices may be restored to normal condition, means whereby actuation of the error key will prevent operation of the motor-trip device by said member, and locking means for said error key controlled by the general operator.

15. In combination computing mechanism

12. In combination, computing mechanism comprising devices in which numbers may be indexed and a general operator whereby numbers so indexed may be computed, a
30 motor, motor-actuated means for actuating said general operator, a motor-trip device, a member by which said motor-trip device may be operated, an error key, error-key-actuated means whereby the index devices
35 may be restored to normal condition, means whereby actuation of the error key will prevent operation of the motor-trip device by said member, and an error-key lock normally held in ineffective condition by said general
40 operator, but permitted to become effective upon movement of the general operator from its normal position.

16. In combination computing mechanism

13. In combination, computing mechanism comprising numeral keys, devices in which numbers may be indexed in accordance with the numeral keys depressed, and a general operator whereby numbers so indexed may be computed, a motor, motor-actuated means for actuating said general operator, a motor-trip device, a member by which said motor-trip device may be operated, an error key, error-key-actuated means whereby the index devices may be restored to normal condition including means for locking said member against movement, and locking means for said numeral keys rendered effective upon actuation of said error key.

comprising numeral keys, devices in which numbers may be indexed in accordance with the numeral keys depressed, and a general operator whereby numbers so indexed may be computed, a motor, motor-actuated means for actuating said general operator, a motor-trip device, a member by which said motor-trip device may be operated, an error key, error-key-actuated means whereby the index devices may be restored to normal condition, including a member which, upon operation of said error key, will be moved into engagement with the motor-trip member and lock the same against movement, and locking means for said numeral keys rendered effective upon actuation of said error key.

14. In combination, computing mechanism comprising devices in which numbers may be indexed and a general operator whereby numbers so indexed may be computed, a motor, motor-actuated means for actuating said general operator, a motor-trip device, a member by which said motor-trip device may be operated, an error key, error-key-

17. In combination, computing mechanism comprising devices in which numbers may be indexed and a general operator whereby numbers so indexed may be computed, a motor, motor-actuated means for actuating said general operator, a motor-trip device, a member by which said motor-trip device may be operated, an error key, error key-actuated means whereby the index devices may be restored to normal condition, including a member which, upon operation of said error key, will be moved into engagement with the motor-trip member and lock the same against movement, and locking means for said error key controlled by the general operator. 105 110 115

18. In combination, computing mechanism 120 comprising devices in which numbers may be indexed and a general operator whereby numbers so indexed may be computed, a motor, motor-actuated means for actuating said general operator, a motor-trip device, 125 a member by which said motor-trip device may be operated, an error key, error-key-actuated means whereby the index devices may be restored to normal condition, including a member which, upon operation of 130

6
said error key, will be moved into engagement with the motor-trip-operating member and lock the same against movement, and an error-key lock normally held in ineffective condition by said general operator, but permitted to become effective upon movement of the general operator from its normal position.

19. In combination, computing mechanism comprising numeral keys, devices in which numbers may be indexed in accordance with the numeral keys depressed, and a general operator whereby numbers so indexed may be computed, a motor, a motor-trip device, a member to operate said motor-trip device directly, a motor-trip key, a lever actuatable by said motor-trip key and positioned to engage the motor-trip device, an error key, error-key-actuated means whereby the index devices may be restored to normal condition, error-key-actuated means for locking said member and the lever controlled by said motor-trip key against movement, and locking means for said numeral keys rendered effective upon actuation of said error key.

20. In combination, computing mechanism comprising devices in which numbers may be indexed and a general operator whereby numbers so indexed may be computed, a motor, a motor-trip device, a key to operate said motor-trip device directly, a second key, a lever actuatable by said second key and positioned to engage the motor-trip device, an error key, error-key-actuated means whereby the index devices may be restored to normal condition, error-key-actuated means for locking said first key and the lever controlled by said second key against movement, and locking means for said error key controlled by said general operator.

21. In combination, computing mechanism comprising devices in which numbers may be indexed and a general operator whereby numbers so indexed may be computed, a motor, a motor-trip device, a key to operate said motor-trip device directly, a second key, a lever actuatable by said second key and positioned to engage the motor-trip device, an error key, error-key-actuated means whereby the index devices may be restored to normal condition, error-key-actuated means for locking said first key and the lever controlled by said second key against movement, and an error-key lock normally held in ineffective condition by said general operator, but permitted to become effective upon movement of the general operator from its normal position.

22. In combination, computing mechanism comprising numeral keys, devices in which numbers may be indexed in accordance with the numeral keys depressed, and a general operator whereby numbers so indexed may

be computed, a motor, a motor-trip device, a manually operable device for operating said motor trip device, a separate device for operating said motor-trip device, an error key, error-key-controlled means for blocking both of the last mentioned devices to prevent operation thereby of the motor-trip device, and locking means for said numeral keys rendered effective upon actuation of said error key.

23. In combination, computing mechanism comprising devices in which numbers may be indexed and a general operator whereby numbers so indexed may be computed, a motor, a motor-trip device, a manually operable device for operating said motor-trip device, a separate device for operating said motor-trip device, an error key, error-key-controlled means for blocking both of the last-mentioned devices, to prevent operation thereby of the motor-trip device, and locking means for said error key controlled by the general operator.

24. In combination, computing mechanism comprising devices in which numbers may be indexed and a general operator whereby numbers so indexed may be computed, a motor, a motor-trip device, a manually operable device for operating said motor-trip device, an error key, error-key-controlled means for blocking both of the last-mentioned devices, to prevent operation thereby of the motor-trip device, and an error-key lock normally held in ineffective condition by said general operator, but permitted to become effective upon movement of the general operator from its normal position.

25. In combination, computing mechanism comprising devices in which numbers may be indexed and a general operator whereby numbers so indexed may be computed, a manually operable member, means whereby actuation of said member will cause actuation of the general operator, an error key, error-key-actuated means whereby the index-devices may be restored to normal condition, and means whereby actuation of said error key will prevent operation of said member.

26. In combination, computing mechanism comprising numeral keys, devices in which numbers may be indexed in accordance with the numeral keys depressed, and a general operator whereby numbers so indexed may be computed, a manually operable member, means whereby actuation of said member will cause actuation of the general operator, an error key, error-key-actuated means whereby the index devices may be restored to normal condition, means whereby actuation of said error key will prevent operation of said member, and locking means for said numeral keys rendered effective upon actuation of said error key.

27. In combination, computing mechanism

- comprising devices in which numbers may be indexed, and a general operator whereby numbers so indexed may be computed, a manually operable member, means whereby 5 actuation of said member will cause actuation of the general operator, an error key, error-key-actuated means whereby the index devices may be restored to normal condition, means whereby actuation of said error key 10 will prevent operation of said member, and locking means for said error key controlled by the general operator.
28. In a combined typewriting and computing machine, in combination, typewriting mechanism including numeral keys to type digits when depressed, computing mechanism comprising denominational devices in which digits may be indexed, one by one, concomitantly with the typing thereof, and 15 a general operator whereby numbers of which the digits have been so indexed and typed may be computed, a manually operable member, means whereby actuation of said member will cause actuation of the 20 general operator, an error key, error-key-actuated means whereby the index devices may be restored to normal condition, means whereby actuation of said error key will prevent operation of said member, and an 25 error-key lock normally held in ineffective condition by said general operator, but permitted to become effective upon movement of the general operator from its normal position.
35. 29. In combination, computing mechanism comprising devices in which numbers may be indexed and a general operator whereby numbers so indexed may be computed, a manually operable member, means whereby 40 by actuation of said member will cause actuation of the general operator, an error key, error-key-actuated means whereby the index-devices may be restored to normal condition, and error-key-locking means rendered effective upon operation of said member and so maintained until said member is 45 restored to normal position.
30. In a combined typewriting and computing machine, in combination, typewriting mechanism including numeral keys to type digits when depressed, computing mechanism comprising denominational devices in which numbers may be indexed and a general operator whereby numbers of which 50 the digits have been so indexed and typed may be computed, an error key, error-key-actuated means whereby the index devices may be restored to normal condition, and locking means for said error key controlled 55 by the general operator.
31. In a combined typewriting and computing machine, in combination, typewriting mechanism including numeral keys to type digits when depressed, computing mechanism comprising denominational devices in 60 which numbers may be indexed and a general operator whereby numbers of which the digits have been so indexed and typed may be computed, an error key, error-key-actuated means whereby the index devices may be restored to normal condition, and means to prevent operation of said error 65
- which numbers may be indexed and a general operator whereby numbers of which the digits have been so indexed and typed may be computed, an error key, error-key-actuated means whereby the index devices may be restored to normal condition, and an error-key lock normally held in ineffective position by said general operator, but permitted to become effective by movement of the general operator from its normal position. 70
32. In combination, computing mechanism comprising devices in which numbers may be indexed and a general operator whereby numbers so indexed may be computed, actuating means for said general operator, an error key, error-key-actuated means whereby the index devices may be restored to normal condition, and locking means for said error key controlled by the actuating means for 80 said general operator.
33. In combination, computing mechanism comprising devices in which numbers may be indexed and a general operator whereby numbers so indexed may be computed, a motor, motor-actuated means for actuating said general operator, a motor-trip device, a member by which said motor-trip device may be operated, an error key, error-key-actuated means whereby the index devices 90 may be restored to normal condition, and locking means for said error key controlled by said member. 95
34. In a combined typewriting and computing machine, in combination, typewriting mechanism including numeral keys to type digits when depressed, computing mechanism comprising denominational devices in which digits may be indexed, one by one, concomitantly with the typing thereof, and a general operator whereby numbers of which the digits have been so indexed and typed may be computed, a motor, motor-actuated means for actuating said general operator, a motor-trip device, a member by 100 which said motor-trip device may be operated, an error key, error-key-actuated means whereby the index devices may be restored to normal condition, an error-key lock, a numeral-key lock, and means whereby 105 actuation of said member will render both of said locks effective. 110
35. In a combined typewriting and computing machine, in combination typewriting mechanism including numeral keys to type digits when depressed, computing mechanism comprising denominational devices in which digits may be indexed, one by one, concomitantly with the typing thereof, and a general operator whereby numbers of 120 which the digits have been so indexed and typed may be computed, an error key, error-key-actuated means whereby the index-devices may be restored to normal condition, and means to prevent operation of said error 125 130

key while computation is being effected by said operating means.

36. In combination, computing mechanism comprising devices in which numbers may be indexed and operating means whereby numbers so indexed may be computed, an error key, error-key-actuated means whereby the index devices may be restored to normal condition, and means to prevent operation of the error key while said operating means is effecting computation, and to prevent the operation of said operating means while the error key is depressed.

37. In a combined typewriting and computing machine, in combination, typewriting mechanism including numeral keys to type digits when depressed, computing mechanism comprising denominational devices in which digits may be indexed, one by one, concomitantly with the typing thereof, and a general operator whereby numbers of which the digits have been so indexed and typed may be computed, an error key, error-key-actuated means whereby the index devices may be restored to normal condition, and means whereby said error key will be locked while computation is being effected by said operating means.

38. In a combined typewriting and computing machine, in combination, typewriting mechanism including numeral keys to type digits when depressed, computing

mechanism comprising denominational devices in which digits may be indexed, one by one, concomitantly with the typing thereof, and a general operator whereby numbers of which the digits have been so indexed and typed may be computed, an error key, error-key-actuated means whereby the index devices may be restored to normal condition, and means whereby locking of said numeral keys will be effected upon actuation of said error key.

39. In a combined typewriting and computing machine, in combination, typewriting mechanism including numeral keys to type digits when depressed, computing mechanism comprising denominational devices in which digits may be indexed, one by one, concomitantly with the typing thereof, and a general operator whereby numbers of which the digits have been so indexed and typed may be computed, an error key, error-key-actuated means whereby the index-devices may be restored to normal condition, a numeral-key lock, an error-key lock, a member for controlling said operating means, and means whereby actuation of said member will render said numeral-key lock and said error-key lock effective.

HENRY L. PITMAN.
